UNITED STATES PATENT OFFICE.

CHARLES J. HEYLMANN, OF CHICAGO, ILLINOIS.

DESIGN FOR A GAME-BOARD.

52,394.

Specification for Design.

Patented Sept. 10, 1918.

Application filed March 19, 1918. Serial No. 223,473. Term of patent 7 years.

To all whom it may concern:

Be it known that I, CHARLES J. HEYLMANN, a citizen of the United States, and residing at Chicago, in the county of Cook and State of Illinois, have invented a new, original, and ornamental Design for a Game-Board, of which the following is a specification, reference being had to the accompanying drawing, forming a part thereof.

This design has reference to a game board of the checkers or chess type. It is of octagonal contour, the top and bottom, and two sides being slightly longer than the remaining oblique sides. The board has a border of various short lines. From the middle of each of the diagonal sides extends diagonally a single straight line to divide the board into four, approximately triangular fields or sections, said lines terminating at the corners of a single square located in the center of the board. Each of these sections has a bottom row of three dark squares and two intervening light squares; a second row of four dark and two light squares, a third row of two dark squares, a fourth row also of two dark squares, while the last row has but one dark square and forms the apex of the triangle. In each section there is a cross, the members of which are of equal length and occupy one space in the second, three spaces in the third, and one space in the fourth row.

The figure is a plan view of the game board, showing my new design.

I claim:

The ornamental design for a game board, as shown and described.

CHARLES J. HEYLMANN.
